UNITED STATES PATENT OFFICE.

CLARENCE W. COLEMAN, OF WESTFIELD, NEW JERSEY, ASSIGNOR TO
THE HALL SIGNAL COMPANY, A CORPORATION OF MAINE.

RAILWAY SIGNAL APPARATUS.

SPECIFICATION forming part of Letters Patent No. 758,297, dated April 26, 1904.

Application filed April 4, 1902. Serial No. 101,327. (No model.)

To all whom it may concern:

Be it known that I, CLARENCE W. COLEMAN, a citizen of the United States, and a resident of Westfield, in the county of Union and State of New Jersey, have invented certain new and useful Improvements in Railway Signal Apparatus, of which the following is a specification.

This invention relates to railway signal apparatus.

- 10   The invention seeks to provide an apparatus characterized by simplicity of construction and efficiency and reliability of operation. In carrying out this purpose it employs fluid-pressure for operating the signal. It is more particularly proposed, however, to employ liquefied gas stored in a local reservoir in proximity to the signal which when released assumes the gaseous form for performing the required work.
- 15   The invention seeks to provide an efficient arrangement of valve devices especially designed and arranged for positive and reliable control of fluid-pressure in operating the signal.
- 20   The invention also proposes to provide a suitable system of electric circuits for controlling the operation of the signals. In the present embodiment of the invention hereinafter set forth the signals are arranged to stand normally at "danger," home and distant signals being carried on the same post. The signals may, however, be arranged to stand normally at "safety," if desired. The invention, however, is not in all of its features limited to such details. Moreover, the signals have in their best form a normal bias to danger position and when moved from danger to safety position are held from return movement by a retaining device until released.
- 25   In the accompanying drawings, forming part of this specification, and in which like reference-numerals designate corresponding parts, Figure 1 is a front elevation of the apparatus when the signal is at "danger," partly in section and with parts omitted. Fig. 2 is a side elevation of the apparatus shown in Fig. 1 looking in the direction from right to left of Fig. 1. Fig. 3 is a sectional plan view on the line 3-3 of Fig. 1 with the frame partly broken

away. Fig. 4 is a front elevation showing a device for increasing the leverage of the motor in connection with the home and distant signals, and Fig. 5 is a diagram of the electric circuits and signals constituting the system.

Referring now more specifically to the particular embodiment of the invention shown in the drawings, the signal-post 1 carries in the usual manner the home and distant signals 2 and 3, pivoted on the post.

4 is a frame, substantially U-shaped, secured to the post, and to which are connected the operating parts of the fluid-pressure motor. In the present embodiment of the invention duplicate motors are employed for home and distant signals having the same construction and arrangement. In each of these motors a gas-pressure - applying chamber is employed, which, as shown in the drawings, may be in the form of a piston-chamber and piston.

5 is the piston-chamber for the home signal 2, within which works the piston 6, carrying the piston-rod 7, to which is fixed a hood 8 to inclose the top of the piston-chamber. The piston-chamber is supplied with gas through the pipe 9, which is connected with the pipe 10, leading to a local reservoir 97, containing the liquefied gas.

11 is an automatic reducing-valve located in the pipe 10 for reducing the pressure in accordance with the requirements of proper operation.

12 is a valve-casing connected with the pipe 9 and provided with an exhaust-port 13, controlled by an exhaust-valve 14, and also provided with a supply-port controlled by an inlet or supply valve 15. These valves are carried on the valve-stem 16, operated by the bell-crank lever 17, carrying an armature associated with the magnet 18. In the preferred arrangement supply-valve 15 is biased toward closed position and exhaust-valve 14 is biased toward open position. This may be provided for by the weight of the parts or otherwise. The valve-casing is also provided with a cut-off valve 19, which may be of any suitable form, but which, as shown in the drawings, is in the form of a diaphragm and which seats against a plate 20 within the valve-cas-

ing. The cut-off valve 19 has a bias to closed position, which may be provided for by the spring 21 on the stem of the cut-off valve. The cut-off valve is restrained from closing by a pivoted member or lever 22, working on a pivot 23, and the lower end of this lever is pivotally connected to the stem of the cut-off valve. The lever 22 is held in position to restrain the cut-off valve by means of a suitable locking means or latch or catch, which may be in the form of a dog 24, secured to the frame on the pivot-pin 25.

Secured to the piston-rod 7 is an adjustable block 26, having a stud 27, carrying at its outer end the roller 28. The dog 24 has secured to it a downwardly-extending arm 29, whose lower end is sheaved or inclined, as shown in Fig. 1, and whose lower end terminates a suitable distance above the stud 27 when the piston 6 is in its lower position, as shown in Fig. 1. When the piston rises, the roller 28 works against the arm 29, thereby lifting the dog 24 to release the lever 22, which thereby causes the cut-off valve 19 to close. The block 26 on the piston-rod 7 carries a spring-dog 30, which when the piston rises to put the signal to "safety," against its normal bias is arranged to engage a retaining device to hold the signal against return movement. In the present embodiment this retaining device is shown in the form of a latch 31, carried on the rock-shaft 32, to which is also fixed a controlling-arm 33, provided with an armature controlled by the magnet 18, the arrangement being such that when the magnet is energized the arm 33 will be held firmly to the magnet, so that the latch 31 may be held in position to engage the spring-dog 30, and thereby hold the signal against return movement. The lever 22 is provided with the offset 34, against which the roller 28 on the arm 27 works when the piston descends from its upper to its lower position. The purpose of this offset is to push back the lever 22 into position for engagement by the dog 24 when the latter is permitted to fall. This movement of the lever 22 of course again opens the cut-off valve 19. The arm 33 normally hangs with its armature against the pole of the magnet 18 and for this purpose is shown as provided with the counterweight 35.

Of course the retaining device and associated means may be variously modified without departing from the scope of the invention.

36 is a circuit-closer working against a contact 37 and operated by a weighted lever 38, which is controlled by a rod 39. This rod is secured to a bar 40, adapted to work up and down on pin 41, projecting from the upper part of the frame 4. When the block 26 rises, it lifts the bar 40, thereby closing contacts 36 and 37. These contacts control the movement of the distant signal to "safety," and by means of these contacts the movement of the

distant signal to "safety" is prevented until after the home signal has gone to "safety." This will more fully appear in connection with the circuits hereinafter to be described.

The purpose of the arm 29 is to enable the inflow of gas to the piston-chamber 5 to be cut off before the piston has completed its upward movement, the expansion of the gas previously admitted to the piston-chamber being relied upon to complete the upward movement of the piston. This effects a saving in the quantity of gas consumed in shifting the signal. Of course if this advantage is not desired the arm 29 can be omitted. In this case the cut-off valve would be closed when the arm 26 rises high enough to lift the dog 24 from engagement with the arm 22. At this time the signal will be at "safety."

A device for increasing the leverage of the motor may be used in connection with the signal, if desired. Referring now to this device, 42 is a yoke carried by an upper extension of the frame 4. A lever 43 is pivoted at one end to one side of this yoke and at its other end to the signal-rod 44 of the home signal. 45 is a link pivotally connected at its lower end to the piston-rod 7 and at its upper end to a lever 46. The lever 46 is pivoted at one end to the extension of the frame 4 and at its opposite end carries a roller 47, bearing against the lower side of the lever 43 intermediate the ends of the lever 43. When the signal is at "danger" and the piston in its lower position, as shown in Fig. 1, the levers 43 and 46 are in the position shown in Fig. 1. When the piston rises to put the signal to "safety," the lever 46 is inclined upward, lifting the lever 43 to an inclined position, as shown in Fig. 4. In this movement the point where the lever 46 bears against the lever 43 moves gradually outward from the pivoted end of the lever 43, so that the resistance to the upward movement of the piston gradually decreases as the movement of the signal to "safety" proceeds. This diminishing resistance compensates for the diminishing power of the expanding gas in the piston-chamber as it lifts the piston. By this arrangement it is feasible to make use of a power which shifts the signal from one position to another without substantial loss in the efficiency of that power. For example, it is feasible, as contemplated in the apparatus herein described and shown, to shut off the gas before the signal completes its movement to "safety" and rely upon the expansion of the gas already within the piston-chamber, as heretofore described. This device operates to equalize the otherwise changing ratio between the power to shift the signal and the resistance which this power must overcome. It may be employed to accomplish its purpose in a case where the power remains constant and the resistance would otherwise increase, or in a case where the power decreases and the resistance

would otherwise be constant, or in a case where the power decreases and the resistance would otherwise increase, or in a case where the power decreases and the resistance would otherwise decrease less than the power. In the apparatus herein shown the power decreases, owing to the fact that the gas is cut off before the upward movement of the piston is completed, and the resistance would increase except for the employment of the device for increasing leverage. This device may be arranged in a variety of forms.

Inasmuch as the apparatus for the distant signal is a duplicate of that already described for the home signal, it will not be necessary to describe it further than to point out its various parts.

48 is a piston-chamber for the distant signal, and 49 the piston-rod, carrying a block 50, similar to the block 26.

51 is the supply-pipe for the piston-chamber and connects with the pipe 10.

52 is a valve-casing provided with inlet and outlet valves 53 and 54, respectively, which are operated by the magnet 55.

56 is a cut-off valve controlled by the lever 57, which is released by the dog 58, working in the same way as the dog 24.

59 is an arm carried by the dog 58 and similar to the arm 29.

60 is a latch similar to the latch 31 and is operated by the arm 61, similar to the arm 33. The arm 61 is controlled by the magnet 55. The signal-rod 62 is connected with the lever 63, operated upon by the lever 64, which is connected by the link 65 to the piston-rod 49. The levers 63 and 64 operate for the distant signal identically with levers 43 and 46, heretofore described for the home signal.

40 If desired, each of the signals may have a separate storage-tank for liquefied gas and a separate reducing-valve associated with each tank.

The system shown in Fig. 5 contemplates an arrangement of the home and distant signals in blocks, the signals being equipped with apparatus such as that shown in Figs. 1 to 4, inclusive. In Fig. 5 a track is shown divided into blocks 66, 67, and 68. At the entrance of block 67 are located the home and distant signals 2 and 3, and at the entrance of block 68 are located the home and distant signals 69 and 70. The signal-circuit for home signal 2 may be traced from battery 71, common return-wire 72, wire 73, normally open contacts 74, home-signal magnet 18, (shown also in Figs. 1 and 2,) and normally closed contacts 75 back to battery. The signal-circuit for the distant signal 3 may be traced from battery 76, wire 72, wire 73, normally open contacts 77, normally open contacts 37 and 36, (shown also in Figs. 1 and 2,) distant-signal magnet 55, (shown also in Fig. 1,) wire 78, signal-magnet 79 for home signal 69, contacts 80, and wire 81 back to battery. The

circuit of the block 66 includes the track-magnets 82 and 83. The circuit of the block 67 includes the track-magnets 84 and 85. The circuit of the block 68 includes the track-magnets 86 and 87.

In the operation of the system a train on block 66 shunts the current through magnet 83, thereby closing the signal-circuit for the home signal 2 at the normally open contacts 74. The magnet 18 is thereupon energized. 75

Thereupon the magnet 18 closes the exhaust-port 13 and opens the inlet-port. (See Figs. 1 and 2.) The gas then enters the piston-chamber 5, and the piston 6 rises to move the signal 2 to "safety." When the magnet 18 is 80 thus energized, it holds positively the arm 33 in the position shown in Fig. 2. As the piston 6 rises it pushes aside the arm 29, thereby lifting the dog 24 from engagement with the lever 22, and thus closes the cut-off valve 85

19. The gas already admitted to the piston-chamber expands and continues the upward movement of the piston until the dog 30 snaps past the latch 31. The signal 2 is then at "safety." The upward movement of the 90 block 26 lifted the bar 40, and thereby closed the contacts 36 and 37. As soon as this takes place the circuit for the distant signal 3 and home signal 69 is completed, the normally open contacts 77 in this circuit having been 95 closed when the magnet 83 was shunted to close the contacts 74. The distant signal 3 and home signal 69 thereupon go to "safety," the apparatus operating in the way just described with reference to the home signal. 100 When the train enters block 67, it shunts magnets 84, thereby opening at 75 the signal-circuit of home signal 2, and thus deenergizes magnet 18. Magnet 18 thereupon releases the valves 14 and 15, so that the inlet-port is 105 closed and the outlet-port 14 is opened. The magnet 18 also releases the lever 33, whereupon the weight of the signal causes the dog 30 to push the latch 31 out of the way, so that the signal returns to "danger" and the piston 6 descends. This movement of the piston opens contacts 36 and 37 in the distant-signal circuit and causes the distant signal to go to "danger." The presence of the train in block 110 67 also deenergizes magnet 85, whereupon 115 the home signal 69 is continued at "safety" and the home signal 95 and distant signal 70 are put to "safety" in advance of the train, the operation being the same as that heretofore described with respect to signals 2, 3, and 120 69. In the same way when the train enters block 68 the signals 69 and 70 go to "danger," and the contacts 75 being now closed a following train entering block 66 may put the home signal 2 to "safety." This following 125 train, however, in block 66 cannot put the distant signal 3 or home signal 69 to "safety," because the train in block 68 keeps the contacts 80 at this time open.

While the various features of the invention 130

are shown in what is believed to be the best form and arrangement, it is to be understood that many of the advantages of the invention may be obtained by various changes in the details of structure and arrangement of such features without departing from the scope of the invention. For example, various forms of pressure-applying chambers other than a piston-chamber may be used. Again, if desired, the fluid within the pressure-applying chamber may be exhausted or allowed to escape therefrom immediately after the signal has been brought to a position where its return movement is prevented by the retaining device. This modification is not specifically claimed herein; but it is reserved for another pending application—to wit, application filed March 1, 1904, Serial No. 196,088, for a railway signal apparatus. Furthermore, some features of the invention may be used in connection with a fluid-pressure signal wherein the source of fluid-pressure supply is other than liquefied gas. In such cases the gas-pressure-applying chamber would still be utilized.

The device for increasing leverage (shown in Fig. 4) and the system of circuits are not specifically claimed herein, the same being reserved for other pending applications—to wit, application filed March 1, 1904, Serial No. 196,088, for a railway signal apparatus, and application filed June 7, 1902, Serial No. 110,577, for a signal apparatus and systems:

What I claim, and desire to secure by Letters Patent, is—

1. In a fluid-pressure signal apparatus, the combination of a signal; a continuously-maintained fluid-pressure-supply source; a fluid-pressure-applying chamber in operative connection with the signal and in communication with said supply source; supply and exhaust valves for said chamber; means for operating said valves whereby fluid-pressure may be supplied to and maintained in said chamber to move the signal from one position to another and there maintain it by said fluid-pressure; and a retaining device to prevent return movement of the signal.

2. In a fluid-pressure signal apparatus, the combination of a signal; a fluid-pressure-supply source; a fluid-pressure-applying chamber in operative connection with the signal and in communication with said supply source; supply and exhaust valves for said chamber; means under electric control for operating said valves whereby fluid-pressure may be supplied to and maintained in said chamber to move the signal from one position to another and there maintain it by said fluid-pressure; and a retaining device under electric control to prevent return movement of the signal.

3. In a fluid-pressure signal apparatus, the combination of a signal; a fluid-pressure supply source; a fluid-pressure-applying chamber in operative connection with the signal and in

communication with said supply source; supply and exhaust valves for said chamber; means for operating said valves whereby fluid-pressure may be supplied to and maintained in said chamber to move the signal from one position to another and there maintain it by said fluid-pressure; a retaining device to prevent return movement of the signal; and a track-circuit for controlling said valve-operating means and said retaining device.

4. In a fluid-pressure signal apparatus, the combination of a signal; a fluid-pressure-supply source; a fluid-pressure-applying chamber in operative connection with the signal and in communication with said supply source; supply and exhaust valves for said chamber; means for operating said valves whereby fluid-pressure may be supplied to and maintained in said chamber to move the signal from one position to another and there maintain it by said fluid-pressure; a retaining device to prevent return movement of the signal; and a signal-circuit for operating said valve-operating means and said retaining device.

5. In a fluid-pressure signal apparatus, the combination of a signal; a continuously-maintained fluid-pressure-supply source; a fluid-pressure-applying chamber in operative connection with the signal and in communication with said supply source; supply and exhaust valves for said chamber; means for opening the supply-valve whereby fluid-pressure may be admitted to said chamber to move the signal from one position to another and there maintain it by fluid-pressure; a retaining device to prevent return movement of the signal; and means for releasing said retaining device and opening the exhaust-valve to permit a return movement of the signal.

6. In a fluid-pressure signal apparatus, the combination of a signal; a continuously-maintained fluid-pressure-supply source; a fluid-pressure-applying chamber in operative connection with the signal and in communication with said supply source; supply and exhaust valves for said chamber; means for opening the supply-valve whereby fluid-pressure may be admitted to said chamber to move the signal from one position to another and there maintain it by fluid-pressure; a retaining device to prevent return movement of the signal; and train-operated means for releasing said retaining device and opening the exhaust-valve to permit a return movement of the signal.

7. In a fluid-pressure signal apparatus, the combination of a signal; a fluid-pressure-supply source; a fluid-pressure-applying chamber in operative connection with the signal and in communication with said supply source; supply and exhaust valves for said chamber; means for opening the supply-valve whereby fluid-pressure may be admitted to said chamber to move the signal from one position to another and there maintain it by fluid-pressure.

sure; a retaining device to prevent return movement of the signal; and a track-circuit for releasing said retaining device and opening the exhaust-valve to permit a return movement of the signal.

8. In a fluid-pressure signal apparatus, the combination of a signal; a continuously-maintained fluid-pressure-supply source; a fluid-pressure-applying chamber in operative connection with the signal and in communication with said supply source; supply and exhaust valves for said chamber; means for operating said valves whereby fluid-pressure may be supplied to and maintained in said chamber to move the signal from one position to another and there maintain it by said fluid-pressure; means for automatically cutting off the fluid-pressure supply to said chamber upon a predetermined movement of the signal; and a retaining device to prevent return movement of the signal.

9. In a fluid-pressure signal apparatus, the combination of a signal; a fluid-pressure-supply source; a fluid-pressure-applying chamber in operative connection with the signal and in communication with said supply source; supply and exhaust valves for said chamber; means under electric control for operating said valves whereby fluid-pressure may be supplied to and maintained in said chamber to move the signal from one position to another and there maintain it by said fluid-pressure; means for automatically cutting off the fluid-pressure supply to said chamber upon a predetermined movement of the signal; and a retaining device under electric control to prevent return movement of the signal.

10. In a fluid-pressure signal apparatus, the combination of a signal; a continuously-maintained fluid-pressure-supply source; a fluid-pressure-applying chamber in operative connection with the signal and in communication with said supply source; supply and exhaust valves for said chamber; means for opening the supply-valve whereby fluid-pressure may be admitted to said chamber to move the signal from one position to another and there maintain it by fluid-pressure; a retaining device to prevent return movement of the signal; means for automatically cutting off the fluid-pressure supply to said chamber upon a predetermined movement of the signal; and means for releasing said retaining device and opening the exhaust-valve to permit a return movement of the signal.

11. In a fluid-pressure signal apparatus, the combination of a signal; a continuously-maintained fluid-pressure-supply source; a fluid-pressure-applying chamber in operative connection with the signal and in communication with said supply source; supply and exhaust valves for said chamber; means for opening the supply-valve whereby fluid-pressure may be admitted to said chamber to move the signal from one position to another and there

maintain it by fluid-pressure; a retaining device to prevent return movement of the signal; means for automatically cutting off the fluid-pressure supply to said chamber upon a predetermined movement of the signal; and a train-operated means for releasing said retaining device and opening the exhaust-valve to permit a return movement of the signal.

12. In a fluid-pressure signal apparatus, the combination of a signal having a normal bias to danger; a continuously-maintained fluid-pressure-supply source; a fluid-pressure-applying chamber in operative connection with said supply source; supply and exhaust valves for said chamber; means for operating said valves whereby fluid-pressure may be supplied to and maintained in said chamber to move the signal to safety against its normal bias and there maintain it by said fluid-pressure; and a retaining device to prevent return movement of the signal.

13. In a fluid-pressure signal apparatus, the combination of a signal having a normal bias to danger; a fluid-pressure-supply source; a fluid-pressure-applying chamber in operative connection with the signal and in communication with said supply source; supply and exhaust valves for said chamber; means for operating said valves whereby fluid-pressure may be supplied to and maintained in said chamber to move the signal to safety against its normal bias and there maintain it by said fluid-pressure; a retaining device to prevent return movement of the signal; and a track-circuit for controlling said valve-operating means and said retaining device.

14. In a fluid-pressure signal apparatus, the combination of a signal having a normal bias to danger; a continuously-maintained fluid-pressure-supply source; a fluid-pressure-applying chamber in operative connection with said supply source; supply and exhaust valves for said chamber; means for opening the supply-valve whereby fluid-pressure may be admitted to said chamber to move the signal to safety against its normal bias and there maintain it by fluid-pressure; a retaining device to prevent return movement of the signal; and means for releasing said retaining device and opening the exhaust-valve to permit a return movement of the signal.

15. In a fluid-pressure signal apparatus, the combination of a signal having a normal bias to danger; a fluid-pressure-supply source; a fluid-pressure-applying chamber in operative connection with the signal and in communication with said supply source; supply and exhaust valves for said chamber; means under electric control for operating said valves whereby fluid-pressure may be supplied to and maintained in said chamber to move the signal to safety against its normal bias and there maintain it by said fluid-pressure; means for automatically cutting off the fluid-pressure supply to said chamber upon a predetermined

movement of the signal; and a retaining device under electric control to prevent return movement of the signal.

16. In a fluid-pressure signal apparatus, the combination of a signal having a normal bias to danger; a continuously-maintained fluid-pressure-supply source; a fluid-pressure-applying chamber in operative connection with the signal and in communication with said supply source; supply and exhaust valves for said chamber; means for opening the supply-valve whereby fluid-pressure may be admitted to said chamber to move the signal to safety against its normal bias and there maintain it by fluid-pressure; a retaining device to prevent return movement of the signal; means for automatically cutting off the fluid-pressure supply to said chamber upon a predetermined movement of the signal; and train-operated means for releasing said retaining device and opening the exhaust-valve to permit a return movement of the signal.

17. In a fluid-pressure signal apparatus, the combination of a signal; a fluid-pressure-supply source; a fluid-pressure-applying chamber in operative connection with the signal and in communication with said supply source; supply and exhaust valves for said chamber; means for opening the supply-valve whereby fluid-pressure may be admitted to said chamber to move the signal from one position to another and there maintain it by fluid-pressure; a retaining device to prevent return movement of the signal; and a magnet for releasing said retaining device and opening the exhaust-valve to permit a return movement of the signal.

18. In a fluid-pressure signal apparatus, the combination of a signal; a fluid-pressure-supply source; a fluid-pressure-applying chamber in operative connection with the signal and in communication with said supply source; supply and exhaust valves for said chamber; means for opening the supply-valve whereby fluid-pressure may be admitted to said chamber to move the signal from one position to another and there maintain it by fluid-pressure; a retaining device to prevent return movement of the signal; a signal-circuit; and a magnet included in said circuit for releasing said retaining device and opening the exhaust-valve to permit a return movement of the signal.

19. In a fluid-pressure signal apparatus, the combination of a signal; a fluid-pressure-supply source; a fluid-pressure-applying chamber in operative connection with the signal and in communication with said supply source; supply and exhaust valves for said chamber; means for opening the supply-valve whereby fluid-pressure may be admitted to said chamber to move the signal from one position to another and there maintain it by fluid-pressure; a retaining device to prevent return movement of the signal; means for automatically cutting off the fluid-pressure supply to

said chamber upon a predetermined movement of the signal; a signal-circuit; and a magnet included in said circuit for releasing said retaining device and opening the exhaust-valve to permit a return movement of the signal.

20. In a fluid-pressure signal apparatus, the combination of a signal; an isolated fluid-pressure storage-tank; a fluid-pressure-applying chamber in operative connection with the signal and in communication with said storage-tank; supply and exhaust valves for said chamber; means for operating said valves whereby fluid-pressure may be supplied to and maintained in said chamber to move the signal from one position to another and there maintain it by said fluid-pressure; a retaining device to prevent return movement of the signal; and an automatic reducing-valve for said fluid-pressure-applying chamber.

21. In a gas-pressure signal apparatus, the combination of a signal; a tank for liquefied gas; a gas-pressure-applying chamber in operative connection with said signal and in communication with said tank; supply and exhaust valves for said chamber whereby gas may be supplied to and maintained in said chamber to move the signal from one position to another and there maintain it by gas-pressure; means for operating said valves; and a retaining device to prevent return movement of the signal.

22. In a gas-pressure signal apparatus, the combination of a signal; a tank for liquefied gas; a gas-pressure-applying chamber in operative connection with said signal and in communication with said tank; supply and exhaust valves for said chamber whereby gas may be supplied to and maintained in said chamber to move the signal from one position to another and there maintain it by gas-pressure; means for operating said valves; means for automatically cutting off the gas-supply to said chamber upon a predetermined movement of the signal; and a retaining device to prevent return movement of the signal.

23. In a gas-pressure signal apparatus, the combination of a signal; a tank for liquefied gas; a gas-pressure-applying chamber in operative connection with said signal and in communication with said tank; supply and exhaust valves for said chamber whereby gas may be supplied to and maintained in said chamber to move the signal from one position to another and there maintain it by gas-pressure; means for operating said valves; a retaining device to prevent return movement of the signal; and means for releasing said retaining device and opening said exhaust-valve to permit return movement of the signal.

24. In a gas-pressure signal apparatus, the combination of a signal; a tank for liquefied gas; a gas-pressure-applying chamber in operative connection with said signal and in communication with said tank; pressure-reducing means for said chamber; supply and exhaust

valves for said chamber whereby gas may be supplied to and maintained in said chamber to move the signal from one position to another and there maintain it by gas-pressure; a retaining device to prevent return movement of the signal; and a signal-circuit for operating said supply and exhaust valves and said retaining device.

25. In a gas-pressure signal apparatus, the combination of a signal; a detachable and replaceable tank for liquefied gas; a gas-pressure-applying chamber in operative connection with said signal and in communication with said tank; an automatic reducing-valve; supply and exhaust valves for said chamber whereby gas may be supplied to and maintained in said chamber to move the signal from one position to another and there maintain it by gas-pressure; means for operating said valves; and a retaining device to prevent return movement of the signal.

26. In a gas-pressure signal apparatus, the combination of home and distant signals; gas-pressure-applying apparatus for operating said signals separately; a source of liquefied gas for supplying gas to said gas-pressure-applying apparatus; and means operated upon a predetermined movement of the home signal for controlling the movement of the distant signal.

27. In a gas-pressure signal apparatus, the combination of home and distant signals on the same post; gas-pressure-applying apparatus for operating said signals separately; a detachable and replaceable tank for liquefied gas located in proximity to said post for supplying gas to said apparatus; and means operated upon a predetermined movement of the home signal for controlling the movement of the distant signal.

28. In a gas-pressure signal apparatus, the combination of home and distant signals on the same post; a source of liquefied gas; a separate gas-pressure-applying chamber for each signal and in controllable communication with said source of liquefied gas; and means operated upon a predetermined movement of the home signal and controlling the movement of the distant signal.

29. In a gas-pressure signal apparatus, the combination of home and distant signals; a source of liquefied gas; a separate gas-pressure-applying chamber for each signal and in controllable communication with said source of liquefied gas; supply and exhaust valves for each of said chambers; and means controlling the supply-valve of the distant signal and operated upon a predetermined movement of the home signal.

30. In a fluid-pressure signal apparatus, the combination of home and distant signals; a source of fluid-pressure supply for the distant signal; a fluid-pressure-applying chamber in operative connection with the distant signal and in communication with said supply source;

supply and exhaust valves for said chamber whereby fluid-pressure may be supplied to said chamber to move the distant signal from one position to another; a retaining device to prevent return movement of said distant signal; a signal-circuit for controlling the operation of said supply and exhaust valves and said retaining device; and a circuit-controller in said signal-circuit under the control of said home signal whereby the movement of the distant signal to safety is prevented until the home signal has gone to safety.

31. In a gas-pressure signal apparatus, the combination of home and distant signals; a tank for liquefied gas for the distant signal; a gas-pressure-applying chamber in operative connection with the distant signal and in communication with said tank; supply and exhaust valves for said chamber whereby gas may be supplied to said chamber to move the distant signal from one position to another; a retaining device to prevent return movement of said distant signal; a signal-circuit for controlling the operation of said supply and exhaust valves and said retaining device; and a circuit-controller in said signal-circuit under the control of said home signal whereby the movement of the distant signal to safety is prevented until the home signal has gone to safety.

32. In a fluid-pressure signal apparatus, the combination of home and distant signals; a source of fluid-pressure supply for the distant signal; a fluid-pressure-applying chamber in operative connection with said distant signal and in communication with said supply source; supply and exhaust valves for said chamber; means for operating said valves whereby fluid-pressure may be supplied to and maintained in said chamber to move said distant signal from one position to another and there maintain it by said fluid-pressure; a retaining device to prevent return movement of said distant signal; electric means controlling the operation of said valves and said retaining device; and means operated by the movement of the home signal to safety for controlling the operation of said electric means, whereby the movement of the distant signal to safety is prevented until the home signal has gone to safety.

33. In a gas-pressure signal apparatus, the combination of home and distant signals; a tank for liquefied gas for the distant signal; a gas-pressure-applying chamber in operative connection with said distant signal and in communication with said tank; supply and exhaust valves for said chamber; means for operating said valves whereby gas may be supplied to and maintained in said chamber to move said distant signal from one position to another and there maintain it by said gas-pressure; a retaining device to prevent return movement of said distant signal; electric means controlling the operation of said valves and said re-

taining device; and means operated by the movement of the home signal to safety for controlling the operation of said electric means, whereby the movement of the distant signal to safety is prevented until the home signal has gone to safety.

34. In a gas-pressure signal apparatus, the combination of a signal; a tank for liquefied gas; a gas-pressure-applying chamber in operative connection with said signal and in communication with said tank, whereby gas may be supplied from said tank to said gas-pressure-applying chamber to move the signal to another position of indication; supply and exhaust valves for said chamber; means for operating said valves and means for cutting off the supply of gas to said chamber before the signal has completed its movement under gas-pressure, whereby the expansive power of the gas in said chamber may be utilized to complete the movement of the signal.

35. In a gas-pressure signal apparatus, the combination of a signal; a tank for liquefied gas; a gas-pressure-applying chamber in operative connection with said signal and in communication with said tank, whereby gas may be supplied from said tank to said gas-pressure-applying chamber to move the signal to another position of indication; supply and exhaust valves for said chamber; means for operating said valves, means for cutting off the supply of gas to said chamber before the signal has completed its movement under gas-pressure, whereby the expansive power of the gas in said chamber may be utilized to complete the movement of the signal; and a retaining device to prevent return movement of the signal.

36. In a gas-pressure signal apparatus, the combination of a signal; a tank for liquefied gas; a gas-pressure-applying chamber in operative connection with said signal and in communication with said tank, whereby gas may be supplied from said tank to said gas-pressure-applying chamber to move the signal to another position of indication; supply and exhaust valves for said chamber; means for cutting off the supply of gas to said chamber before the signal has completed its movement under gas-pressure, whereby the expansive power of the gas in said chamber may be utilized to complete the movement of the signal; a retaining device to prevent return movement of the signal; and a signal-circuit for operating said supply and exhaust valves and said retaining device.

37. In a gas-pressure signal apparatus, the combination of a signal having a normal bias to one position of indication; a tank for liquefied gas; a gas-pressure-applying chamber in operative connection with said signal and in controllable communication with said tank, whereby gas may be supplied from said tank to said gas-pressure-applying chamber to move the signal against its normal bias to another

position of indication; supply and exhaust valves for said chamber; a cut-off valve normally biased to closed position; and a retaining device to hold said cut-off valve open and adapted to release the cut-off valve when the signal has made a predetermined movement under gas-pressure.

38. In a gas-pressure signal apparatus, the combination of a pivoted semaphore-signal having a normal bias to danger; a tank for liquefied gas; a gas-pressure-applying chamber in operative connection with said signal and in communication with said tank; supply and exhaust valves for said chamber, whereby gas may be supplied to said chamber and maintained therein to move the signal to safety, and there maintain it by gas-pressure; a cut-off valve for said chamber; means for automatically closing the cut-off valve upon a predetermined movement of the signal against its normal bias; and electric devices to control the position of the supply and exhaust valves.

39. In a fluid-pressure signal apparatus, the combination of a signal; means for supplying the fluid-pressure to operate the signal; a valve to cut off the fluid-supply; a pivoted member operating to open said valve; and locking means to hold the pivoted member.

40. In a fluid-pressure signal apparatus, the combination of a signal; means for applying the fluid-pressure to operate the signal; a valve to cut off the fluid-supply; a pivoted member operating to open said valve; and locking means to hold the pivoted member, said locking means being released upon a predetermined movement of the signal.

41. In a fluid-pressure signal apparatus, the combination of a signal; means for applying the fluid-pressure to operate the signal; a valve to cut off the fluid-supply and having a bias toward closed position; a pivoted member operating to open said valve; and a locking means to hold the pivoted member.

42. In a fluid-pressure signal apparatus, the combination of a signal; means for applying the fluid-pressure to operate the signal; a valve to cut off the fluid-supply and having a bias toward closed position; a lever operating to open said valve; and a latch to hold the lever, said latch being released upon a predetermined movement of the signal.

43. In a fluid-pressure signal apparatus, the combination of a signal; means for applying the fluid-pressure to operate the signal; a valve to cut off the fluid-supply; a pivoted member operating to open said valve and arranged to be actuated to open said valve upon a predetermined movement of the signal; and locking means to hold the pivoted member.

44. In a fluid-pressure signal apparatus, the combination of a signal; means for applying the fluid-pressure to operate the signal; a valve to cut off the fluid-supply; a lever operating to open said valve and arranged to be actuated

to open said valve upon a predetermined movement of the signal; and a latch to hold the lever, said latch being released upon a predetermined movement of the signal.

5 45. In a fluid-pressure signal apparatus, the combination of a signal; means for applying the fluid-pressure to operate the signal; a valve to cut off the fluid-supply and having a bias toward closed position; a lever operating to open said valve, and arranged to be actuated to open said valve upon a predetermined movement of the signal; and a latch to hold the lever.

15 46. In a fluid-pressure signal apparatus, the combination of a signal; means for applying the fluid-pressure to operate the signal; a valve to cut off the fluid-supply and having a bias toward closed position; a pivoted member operating to open said valve, and arranged to be actuated to open said valve upon a predetermined movement of the signal; and locking means to hold the pivoted member, said locking means being released upon a predetermined movement of the signal.

25 47. In a fluid-pressure signal apparatus, the combination of a signal; means for applying the fluid-pressure to operate the signal; a cut-off valve; a pivoted member operating to open said valve; locking means to hold the pivoted member; a supply-valve; and a magnet for operating said supply-valve.

35 48. In a fluid-pressure signal apparatus, the combination of a signal; means for applying the fluid-pressure to operate the signal; a cut-off valve; a lever operating to open said valve; a latch to hold the lever; supply and exhaust ports; valve means controlling said ports; and a magnet for operating said valve means.

40 49. In a fluid-pressure signal apparatus, the combination of a signal; means for applying the fluid-pressure to operate the signal; a cut-off valve; a pivoted member operating to open said valve; locking means to hold the pivoted member, said locking means being released upon a predetermined movement of the signal; supply and exhaust valves on the same stem; and a magnet for operating said supply and exhaust valves.

50 50. In a fluid-pressure signal apparatus, the combination of a signal; means for applying the fluid-pressure to operate the signal; a cut-off valve having a bias toward closed position; a pivoted member operating to open said valve; locking means to hold the pivoted member, said locking means being released upon a predetermined movement of the signal; a supply-valve; and a magnet for operating said supply-valve.

55 51. In a fluid-pressure signal apparatus, the combination of a signal; means for applying the fluid-pressure to operate the signal; a cut-off valve; a pivoted member operating to open said valve and arranged to be actuated to open said valve upon a predetermined movement of the signal; locking means to hold the pivoted

member, said locking means being released upon a predetermined movement of the signal; a supply-valve; and a magnet for operating said supply-valve.

70 52. In a fluid-pressure signal apparatus, the combination of a signal; means for applying the fluid-pressure to operate the signal; a cut-off valve having a bias toward closed position; a lever operating to open said valve, and arranged to be actuated to open said valve upon a predetermined movement of the signal; a latch to hold the lever, said latch being released upon a predetermined movement of the signal; a supply-valve; and a magnet for operating said supply-valve.

80 53. In a fluid-pressure signal apparatus, the combination of a signal; means for applying the fluid-pressure to operate the signal; a cut-off valve having a bias toward closed position; a lever operating to open said valve, and arranged to be actuated to open said valve upon a predetermined movement of the signal; and a latch to hold the lever, said latch being released upon a predetermined movement of the signal; supply and exhaust valves on the same stem; and a magnet for operating said supply and exhaust valves.

85 54. In a fluid-pressure signal apparatus, the combination of a signal; means for applying the fluid-pressure to operate the signal; a cut-off valve; a lever operating to open said valve; a latch to hold the lever; and a retaining device to hold the signal in one position.

90 55. In a fluid-pressure signal apparatus, the combination of a signal; means for applying the fluid-pressure to operate the signal; a supply-valve; a cut-off valve having a bias toward closed position; and means controlled by a movement of the signal to cause said cut-off valve to open.

100 56. In a fluid-pressure signal apparatus, the combination of a signal; means for applying the fluid-pressure to operate the signal; a supply-valve; a cut-off valve having a bias toward closed position; and means controlled by a movement of the signal to cause said cut-off valve to open and remain open while the supply-valve is closed.

110 57. In a fluid-pressure signal apparatus, the combination of a signal; means for applying the fluid-pressure to operate the signal; a supply-valve; a cut-off valve having a bias toward closed position; means controlled by a movement of the signal to cause said cut-off valve to open; and means to hold the cut-off valve open, said means being released upon a predetermined movement of the signal.

120 58. In a fluid-pressure signal apparatus, the combination of a signal having a normal bias to danger position; means for applying the fluid-pressure to move the signal to safety position; a cut-off valve; means to open said cut-off valve upon a movement of the signal to danger; a retaining device to hold the signal at safety; a supply-valve; and a magnet to

cause said supply-valve to open and to cause the retaining device to be set.

59. In a fluid-pressure signal apparatus, the combination of a signal having a normal bias to danger position; means for applying the fluid-pressure to move the signal to safety position; a cut-off valve; means to open said cut-off valve upon a movement of the signal to danger; a retaining device to hold the signal at safety; a supply-valve; and a magnet operating when energized to cause supply-valve to open and to cause said retaining device to be set, and operating when deenergized to cause the said retaining device to be released.
60. In a fluid-pressure signal apparatus, the combination of a signal having a normal bias to danger position; means for applying the fluid-pressure to move the signal to safety position; a cut-off valve operating to close automatically; means for opening and holding open said cut-off valve upon a movement of the signal to danger, said means being released upon a movement of the signal to safety; a retaining device to hold the signal at safety; a supply-valve; and electric means controlling said supply-valve and said retaining device.

61. In a fluid-pressure signal apparatus, the combination of a signal having a normal bias to danger position; means for applying the fluid-pressure to move the signal to safety position; a cut-off valve operating to close automatically; means for opening and holding open said cut-off valve upon a movement of the signal to danger, said means being released upon a movement of the signal to safety; a retaining device to hold the signal at safety; a supply-valve; and a magnet controlling said supply-valve and said retaining device, said magnet operating when energized to cause the supply-valve to open and to cause the retaining device to be set, and operating when deenergized to cause the supply-valve to close and said retaining device to be released.

62. In a fluid-pressure signal apparatus, the combination of a signal having a normal bias to danger position; means for applying the fluid-pressure to move the signal to safety position; a cut-off valve operating to close automatically; a lever for opening said cut-off valve upon a movement of the signal to danger; a latch to hold the lever and arranged to be released upon a movement of the signal to safety; a retaining device to hold the signal at safety; a supply-valve; and electric means for controlling said supply-valve and said retaining device.

63. In a fluid-pressure signal apparatus, the combination of a signal having a normal bias to danger position; means for applying the fluid-pressure to move the signal to safety position; a cut-off valve operating to close automatically; a pivoted member for opening said cut-off valve upon a movement of the signal to danger; locking means to hold the pivoted member and arranged to be released upon a

movement of the signal to safety; a retaining device to hold the signal at safety; a supply-valve; and a magnet controlling said supply-valve and said retaining device, said magnet operating when energized to open the supply-valve and set the retaining device and operating when deenergized to close the supply-valve and release the retaining device.

64. In a fluid-pressure signal apparatus, the combination of a signal; a fluid-pressure-supply source; a piston and piston-chamber in communication with said source and in operative connection with said signal; a cut-off valve operating to close automatically; a pivoted member operating to open said valve; locking means to hold said pivoted member when the valve is open; means carried by the piston-rod to move said lever so as to open said valve when the signal goes to danger, and arranged to release said locking means when the signal goes to safety; a supply-valve; and a magnet to operate the supply-valve.

65. In a gas-pressure signal apparatus, the combination of a signal; a liquefied-gas-supply source; a piston and piston-chamber in communication with said source and in operative connection with said signal; a cut-off valve operating to close automatically; a pivoted member operating to open said valve; locking means to hold said pivoted member when the valve is open; means carried by the piston-rod to move said pivoted member so as to open said valve when the signal goes to danger, and arranged to release said locking means when the signal goes to safety; a supply-valve; a magnet to operate the supply-valve; and a retaining device to hold the signal at safety.

66. In a gas-pressure signal apparatus, the combination of a signal; a liquefied-gas source; a piston and piston-chamber in communication with said source and in operative connection with said signal; a cut-off valve operating to close automatically; a pivoted member operating to open said valve; locking means to hold said pivoted member when the valve is open; means carried by the piston-rod to move said pivoted member so as to open said valve when the signal goes to danger; a supply-valve; a retaining device to hold the signal at safety; and electric means operating simultaneously to open said supply-valve and set said retaining device.

67. In a fluid-pressure signal apparatus, the combination of a signal; a fluid-pressure-supply source; a piston and piston-chamber in communication with said source and in operative connection with said signal; a cut-off valve operating to close automatically; a lever operating to open said valve; a latch to hold said lever when the valve is open; means carried by the piston-rod to move said lever so as to open said valve when the signal goes to danger, and arranged to release said latch when the signal goes to safety; a supply-valve; a

retaining device to hold the signal at safety; and a magnet operating when energized to open the supply-valve and set the retaining device, and operating when deenergized to close the supply-valve and release the retaining device.

68. In a fluid-pressure signal apparatus, the combination of a signal; means for applying the fluid-pressure to operate the signal; a supply-valve; a cut-off valve biased toward closed position; and means controlled by a movement of the signal to restrain the closing of the cut-off valve until the signal has made a predetermined movement.

69. In a fluid-pressure signal apparatus, the combination of a signal; means for applying the fluid-pressure to operate the signal; a supply-valve; a cut-off valve biased toward closed position operating to close when the signal goes to safety; and means operating to open said cut-off valve and actuated by the movement of the signal to danger.

70. In a fluid-pressure signal apparatus, the combination of a signal; means for applying the fluid-pressure to operate the signal; a supply-valve; a cut-off valve biased toward closed position; means controlled by a movement of the signal to restrain the closing of the cut-off valve until the signal has made a predetermined movement; and a magnet to operate the supply-valve.

71. In a fluid-pressure signal apparatus, the combination of a signal; means for applying the fluid-pressure to operate the signal; a supply-valve; a cut-off valve biased toward closed position operating to close when the signal goes to safety; means operating to open said cut-off valve and actuated by the movement of the signal to danger; and a magnet to operate the supply-valve.

72. In a fluid-pressure signal apparatus, the combination of a signal; means for applying the fluid-pressure to operate the signal; a supply-valve; a cut-off valve biased toward closed position; means controlled by a movement of the signal to restrain the closing of the cut-off valve until the signal has made a predetermined movement; and a retaining device to hold the signal at one condition of indication.

73. In a fluid-pressure signal apparatus, the combination of a signal; a supply-valve; a cut-off valve operating to close automatically when the signal goes to safety; means operating to open said cut-off valve and actuated by the movement of the signal to danger; and a retaining device to hold the signal at safety.

74. In a fluid-pressure signal apparatus, the combination of a signal; means for applying the fluid-pressure to operate the signal; a supply-valve; a cut-off valve having a bias toward closed position and operating to close automatically when the signal has made a predetermined movement; means controlled by a movement of the signal to restrain the closing

of the cut-off valve until the signal has made such predetermined movement; a retaining device to hold the signal at one condition of indication; and a circuit operating when closed to cause the supply-valve to open and to cause the setting of the retaining device, and operating when deenergized to cause the supply-valve to close and to cause the release of the retaining device.

75. In a fluid-pressure signal apparatus, the combination of a signal; means for applying the fluid-pressure to operate the signal; a supply-valve; a cut-off valve operating to close automatically when the signal has made a predetermined movement; means operating to open said cut-off valve and actuated by the movement of the signal to danger; a retaining device to hold the signal at safety; and a magnet operating when energized to cause the supply-valve to open and to cause the setting of the retaining device, and operating when deenergized to cause the supply-valve to close and to cause the release of the retaining device.

76. In a fluid-pressure signal apparatus, the combination of a signal; means for applying the fluid-pressure to operate the signal; a supply-valve; a cut-off valve biased toward closed position and operating to close when the signal goes to safety and to open when the signal goes to danger; and means controlling said cut-off valve and operated by movement of the signal.

77. In a fluid-pressure signal apparatus, the combination of a signal; means for applying the fluid-pressure to operate the signal; a supply-valve; a cut-off valve biased toward closed position and operating to close when the signal goes to safety and to open when the signal goes to danger; means controlling said cut-off valve and operated by movement of the signal; and a retaining device to hold the signal at safety.

78. In a fluid-pressure signal apparatus, the combination of a signal; means for applying the fluid-pressure to operate the signal; a supply-valve; a cut-off valve operating to close when the signal goes to safety and to open when the signal goes to danger; means controlling said cut-off valve and operated by movement of the signal; a retaining device to hold the signal at safety; and train-controlled means operating to cause the supply-valve to open and to cause the setting of the retaining device.

79. In a fluid-pressure signal apparatus, the combination of a signal; means for applying the fluid-pressure to operate the signal; a valve for cutting off the supply of fluid-pressure when the signal goes to safety and having a bias toward closed position; and a pivoted member actuated by the movement of the signal to danger and operating to open said valve.

80. In a fluid-pressure signal apparatus, the combination of a signal; means for applying

- the fluid-pressure to operate the signal; a valve for cutting off the supply of fluid-pressure when the signal goes to safety and having a bias toward closed position; a pivoted member actuated by the movement of the signal to danger and operating to open said valve; and train-controlled means operating to effect the initial supply of fluid-pressure to put the signal to safety.
81. In a fluid-pressure signal apparatus, the combination of a signal; means for applying the fluid-pressure to operate the signal; a valve for cutting off the supply of fluid-pressure when the signal goes to safety and having a bias toward closed position; a pivoted member actuated by the movement of the signal to danger and operating to open said valve; and a locking device to hold said pivoted member and released when the signal goes to safety.
82. In a fluid-pressure signal apparatus, the combination of a signal; means for applying the fluid-pressure to operate the signal; a valve for cutting off the supply of fluid-pressure and having a bias toward closed position; and means operated by movement of the signal and controlling said valve, whereby said valve is opened when the signal goes to danger and is closed when the signal goes to safety.
83. In a fluid-pressure signal apparatus, the combination of a signal; means for applying the fluid-pressure to operate the signal; a valve for cutting off the supply of fluid-pressure and having a bias toward closed position; and means operated by movement of the signal and controlling said valve, whereby said valve is opened when the signal goes to danger and is closed when the signal goes to safety; and train-controlled means operating to effect the initial supply of fluid-pressure to put the signal to safety.
84. In a signal apparatus, the combination of a signal; storage means containing a supply of liquefied gas; means for applying the gas to operate the signal; a supply-valve; a cut-off valve biased toward closed position; and means controlled by a movement of the signal to restrain the closing of the cut-off valve until the signal has made a predetermined movement.
85. In a signal apparatus, the combination of a signal; storage means containing a supply of liquefied gas; means for applying the gas to operate the signal; a supply-valve; a cut-off valve biased toward closed position, and operating to close when the signal goes to safety; and means operating to open said cut-off valve and actuated by the movement of the signal to danger.
86. In a signal apparatus, the combination of a signal; storage means containing a supply of liquefied gas; means for applying the gas to operate the signal; a supply-valve; a cut-off valve biased toward closed position and operating to close when the signal goes to safety and to open when the signal goes to danger; and means controlling said cut-off valve and operated by movement of the signal.
87. In a signal apparatus, the combination of a signal; storage means containing a supply of liquefied gas; means for applying the gas to operate the signal; a supply-valve; a cut-off valve operating to close when the signal has made a predetermined movement in one direction and to open when the signal has made a predetermined movement in another direction; and means controlling said cut-off valve and operated by movement of the signal; a retaining device to hold the signal in one position; and means operating to cause the supply-valve to open and the retaining device to be set.
88. In a signal apparatus, the combination of a signal; storage means containing a supply of liquefied gas; means for applying the gas to operate the signal; a valve for cutting off the supply of fluid-pressure when the signal goes to safety and having a bias toward closed position; and a pivoted member actuated by the movement of the signal to danger and operating to open said valve.
89. In a signal apparatus, the combination of a signal; storage means containing a supply of liquefied gas; means for applying the gas to operate the signal; a valve for cutting off the supply of fluid-pressure when the signal goes to safety and having a bias toward closed position; a pivoted member actuated by the movement of the signal to danger and operating to open said valve; and train-controlled means operating to effect the initial supply of fluid-pressure to put the signal to safety.
90. In a signal apparatus, the combination of a signal; storage means containing a supply of liquefied gas; means for applying the gas to operate the signal; a valve for cutting off the supply of fluid-pressure when the signal goes to safety and having a bias toward closed position; a pivoted member actuated by the movement of the signal to danger and operating to open said valve; and a locking device to hold said pivoted member and released when the signal goes to safety.
91. In a fluid-pressure mechanism the combination of a motor; an exhaust-port; a valve to cut off the fluid-supply; and means operated from the motor for controlling said valve, said means comprising a part connected with the motor and having a movement coincident therewith, and a second part moved by the first-mentioned part and coacting with said valve.
92. In a fluid-pressure mechanism, the combination of a motor; an exhaust-port; a valve to cut off the fluid-supply; and means operated from the motor for controlling said valve, said means comprising a part connected with the motor and having a movement coincident therewith, a pivoted lever operated by said part and in operative relation to said valve,

and a second lever for holding the first-mentioned lever in one of the positions to which it has been moved.

93. In a fluid-pressure mechanism, the combination of a motor, an exhaust-port; a valve to cut off the supply of fluid-pressure; a pivoted lever in operative relation to said valve; means in engagement with said lever for operating it; a latching-lever for said pivoted lever; and a part connected with the motor for operating said means.

94. In a signal apparatus, the combination of a motor; an exhaust-port; a valve to cut off the fluid-supply; means operating from the motor for controlling said valve, said means comprising a part connected with the motor and having a movement coincident therewith, and a second part moved by the first-mentioned part and coacting with said valve; and a retaining device operating to hold the signal in one position.

95. In a signal apparatus, the combination of a motor; an exhaust-port; a valve to cut off the fluid-supply; means operating from the motor for controlling said valve, said means comprising a part connected with the motor and having a movement coincident therewith, a pivoted lever operated by said part and in operative relation to said valve, and a second lever for holding the first-mentioned lever in one of the positions to which it has been moved; and a retaining device operating to hold the signal in one position.

96. In a signal apparatus, the combination of a motor; an exhaust-port; a valve to cut off the supply of fluid-pressure; a pivoted lever in operative relation to said valve; means in engagement with said lever for operating it; a latching-lever for said pivoted lever; a part connected with the motor for operating said means; and a retaining device operating to hold the signal in one position.

97. In a signal apparatus, the combination of a motor; an exhaust-port; a valve to cut off the fluid-supply; means operated from the motor for controlling said valve, said means comprising a part connected with the motor and having a movement coincident therewith, and a second part moved by the first-mentioned part and coacting with said valve; a supply-valve; a retaining device to hold the signal at safety; and electric means operating when energized to open the supply-valve and set the retaining device and operating when deenergized to close the supply-valve and release the retaining device.

In testimony whereof I have signed my name to this specification in the presence of two subscribing witnesses.

CLARENCE W. COLEMAN.

WM. M. TOWNLEY.

Correction in Letters Patent No. 758,297.

It is hereby certified that in Letters Patent No. 758,297, granted April 26, 1904, upon the application of Clarence W. Coleman, of Westfield, New Jersey, for an improvement in "Railway Signal Apparatus," an error appears in the printed specification requiring correction, as follows: In line 83, page 10, the word "lever" should read *pivoted member*; and that the said Letters Patent should be read with this correction therein that the same may conform to the record of the case in the Patent Office.

Signed and sealed this 17th day of May, A. D., 1904.

[SEAL.]

E. B. MOORE,
Acting Commissioner of Patents.

and a second lever for holding the first-mentioned lever in one of the positions to which it has been moved.

93. In a fluid-pressure mechanism, the combination of a motor, an exhaust-port; a valve to cut off the supply of fluid-pressure; a pivoted lever in operative relation to said valve; means in engagement with said lever for operating it; a latching-lever for said pivoted lever; and a part connected with the motor for operating said means.

94. In a signal apparatus, the combination of a motor; an exhaust-port; a valve to cut off the fluid-supply; means operating from the motor for controlling said valve, said means comprising a part connected with the motor and having a movement coincident therewith, and a second part moved by the first-mentioned part and coacting with said valve; and a retaining device operating to hold the signal in one position.

95. In a signal apparatus, the combination of a motor; an exhaust-port; a valve to cut off the fluid-supply; means operating from the motor for controlling said valve, said means comprising a part connected with the motor and having a movement coincident therewith, a pivoted lever operated by said part and in operative relation to said valve, and a second lever for holding the first-mentioned lever in one of the positions to which it has been moved; and a retaining device operating to hold the signal in one position.

96. In a signal apparatus, the combination of a motor; an exhaust-port; a valve to cut off the supply of fluid-pressure; a pivoted lever in operative relation to said valve; means in engagement with said lever for operating it; a latching-lever for said pivoted lever; a part connected with the motor for operating said means; and a retaining device operating to hold the signal in one position.

97. In a signal apparatus, the combination of a motor; an exhaust-port; a valve to cut off the fluid-supply; means operated from the motor for controlling said valve, said means comprising a part connected with the motor and having a movement coincident therewith, and a second part moved by the first-mentioned part and coacting with said valve; a supply-valve; a retaining device to hold the signal at safety; and electric means operating when energized to open the supply-valve and set the retaining device and operating when deenergized to close the supply-valve and release the retaining device.

In testimony whereof I have signed my name to this specification in the presence of two subscribing witnesses.

CLARENCE W. COLEMAN.

Witnesses:

A. K. GALE,
WM. M. TOWNLEY.

Correction in Letters Patent No. 758,297.

It is hereby certified that in Letters Patent No. 758,297, granted April 26, 1904, upon the application of Clarence W. Coleman, of Westfield, New Jersey, for an improvement in "Railway Signal Apparatus," an error appears in the printed specification requiring correction, as follows: In line 83, page 10, the word "lever" should read *pivoted member*; and that the said Letters Patent should be read with this correction therein that the same may conform to the record of the case in the Patent Office.

Signed and sealed this 17th day of May, A. D., 1904.

[SEAL.]

E. B. MOORE,
Acting Commissioner of Patents.
